United States Patent Office

Des. 187,537
Patented Mar. 29, 1960

187,537

KITCHEN CABINET

Louis Gosecky, Flaxton, N. Dak.

Application February 21, 1958, Serial No. 49,748

Term of patent 14 years

(Cl. D33—19)

The figure is a perspective view of a kitchen cabinet showing my design, wherein the side not shown is like the side shown, while the back is plain and unornamented.

I claim:

The ornamental design for a kitchen cabinet, as shown and described.
